UNITED STATES PATENT OFFICE.

FRANK J. SCHRAEDER, JR., OF WHEATON, ILLINOIS.

LOADING AND UNLOADING APPARATUS.

1,071,096.

Specification of Letters Patent.

Patented Aug. 26, 1913.

Application filed June 3, 1912. Serial No. 701,425.

To all whom it may concern:

Be it known that I, FRANK J. SCHRAEDER, Jr., a citizen of the United States, residing at Wheaton, in the county of DuPage and State of Illinois, have invented a certain new and useful Improvement in Loading and Unloading Apparatus, of which the following is a specification.

My invention belongs to that general class of devices known as coal handling devices and relates more particularly to an apparatus for receiving, measuring, controlling and discharging material into buckets or receptacles which are hoisted or conveyed and discharged into storage bins from which the material may be further conveyed or discharged by gravity or any other system to where desired.

The invention has among its objects the production of a simple, durable, efficient and satisfactory apparatus of the kind described for automatically controlling the flow of material to be transferred and is in the nature of a divisional application for an automatic measuring and loading device shown and described in my application for improvements in conveying systems filed Dec. 27, 1910, Serial No. 599302 issued Jan. 16, 1912 No. 1015251.

To this end my invention consists in the novel construction, arrangement and combination of parts herein shown and described and more particularly pointed out in the claims.

Referring to the drawings in which like reference characters indicate like or corresponding parts; Figure 1 is a sectional elevation of my apparatus showing the loader after its contents has been discharged into the bucket or conveying receptacle. Fig. 2 is a sectional elevation of my loader showing the discharge gate in closed position and the filling gate in open position. Fig. 3 is a sectional front elevation taken at $x-x$ Figs. 1 and 2 showing my invention where two loaders are used in combination with two receptacles. Fig. 4 is a diagrammatic view of my preferred system of gate control. Fig. 5 is a diagrammatic illustration of a loader filling gate in form of construction such as is shown in my patent for conveying system, previously referred to.

In the illustrations I show my invention as applied to a railway coaling station using two loaders and two receptacles which alternately convey the coal or material from

the receiving hopper to the storage bin. As will be seen, it is obvious that by immaterial or simple changes, the system may consist of one loader and one receptacle, or by duplicating the parts shown the station may contain any number of loaders and receptacles. Inasmuch as the loaders and various parts are similar, a detached description of one will suffice.

Referring to Figs. 1, 2 and 3 of the drawings 1 represents a track (partly shown) over which the loaded material or coal cars are brought and discharged into the receiving hopper 2, which slopes toward the loaders and is counter-hoppered so that all of the material is available. The discharge openings of the receiving hopper have chutes 3 projecting toward or into the loader measuring chutes or hoppers 4. The bottom 4^a of the measuring chute slopes downwardly toward the bucket or conveying receptacle 5, and the flow of material from the receiving hopper 2 through the chutes 3 is controlled by the gate 6 which has side 80 arms 7 pivoted at 8. As shown in Fig. 1 the loader filling gate or curved plate 6 is in closed position and prevents the flow of material from the receiving hopper into the loader measuring chute or hopper 4. An 85 apron like discharge gate 9 with sides 9^a and pivoted at 10 controls the flow of material from the loader measuring chute 4 into the bucket or receptacle 5. Fig. 1 shows the discharge gate in open position and by dotted lines in closed position. It may be noted here, that the discharge gate might also be constructed in the form of a vertically slideable plate such as is shown in one of my illustrations of my patent for conveying 95 system referred to. When the discharge gate 9 is in closed position as shown in Fig. 2 and the filling gate 6 with its arms 7 has revolved about its pivot 8 into open position, the coal or material flows by gravity from 100 the receiving hopper into the measuring chute or hopper 4.

The latches 11 arranged at the sides of the measuring hopper 4 are pivoted at 12 and engage the lugs 9^b which project from the sides 9^a and hold the discharge gate 9 in closed position. Operatively connected to these latches at 14 are the bars 13 which extend downwardly to the horizontal bar 15 to which also are attached the operating 110 levers 16 shown in Figs. 1, 2 and 3. The levers 16 are pivotally supported at 17 and

are provided with pivoted ends 18 arranged to coöperate with the extension 19 on the receptacle 5, so that as the receptacle is hoisted in the shaft and the roller 20 closing the gate 9 which is locked by the latches 11, the extension 19 is permitted to pass without operating the latches.

I have preferred to show the receptacle 5 in the form of a skip bucket with rollers 21 and 22 which travel between the guides 23 and 24. Any other bucket or conveying apparatus may be used and any means may be provided for dumping or discharging the conveying receptacle. The receptacle bail side arms 25, pivotally secured to the sides 10 of the receptacle 5 at 26 shown in Fig. 1 are connected with a cross bar 27 at the center 15 of which is attached the hoisting cable 28 which extends to the top of the shaft or discharging point and then passes over sheaves 20 to the hoisting drum. When the skip bucket or receptacle is in its lowest position as shown in Fig. 1 it rests on the supports 29.

Within the path of the conveying receptacle is placed a bar 30 or its equivalent arranged between the guides 31. The cables 32 or their equivalent each have one end fastened to the bar 30 and the other end secured at 36, and to guide these cables I have shown sheaves 33 and 34 with guide grooves 35 on each of the filling gate arms 7. Another set of cables 37 or their equivalent, is secured at 38 also to the filling gate arms 7 and grooves 41 on the gate arms 7 with sheaves 39 and 40 guide the cables 37 to the other loader where they pass around similar grooves 41 and secured to corresponding points 38, thus connecting the two loader filling gates in such manner that when one is in open position the other is in closed position. The connection of the cables 32 and 37 is shown in Figs. 1, 2 and 3 and more clearly in the Fig. 4 which shows my preferred system of connecting the loader filling gates when two loaders are used in a structure. When only one loader is used in combination with one conveying receptacle the ends of cables 37 are secured 40 to a bar similar to 30 which is placed between guides similar to 31 and is operated by the bucket or receptacle counterweight.

Referring to Fig. 4, which is a diagrammatic illustration of my preferred system or manner of operating the loader filling gates when two loaders are used in combination with two receptacles, the filling gate 6 on the left hand side of the illustration is shown in closed position preventing the flow of material from the receiving hopper, through the chute 3 into the measuring chute 4 which has discharged its contents into the receptacle. Before reaching its loading point or the bottom of the shaft, the receptacle engages the bar 30 and in draw-

ing it down, revolves its loader filling gate 6 into closed position and at the same time revolves the filling gate 6 of the other loader into open position as shown on the right hand side of illustration or Fig. 4, the cables 37 or their equivalent connecting the gates in such manner that when one is open the other is closed. After the receptacle 5, coöperating with the left hand filling gate and loader, receives its load, it is hoisted to the top where it discharges into the storage bin and in the meantime the right hand bucket or receptacle descends to the foot of the shaft, engages the bar 30, closing its coöperating filling gate 6 and simultaneously 75 opening the filling gate 6 of the other loader, and then receives its measured quantity of material. This operation is continued until all of the material is conveyed to the storage bin.

Now referring to Fig. 5 I show a diagrammatic illustration of a modified system of control for the filling gates, such as is shown in my patent for "conveying system" #1015251 issued January 16, 1912. Here 90 the loaded receptacle operating the right hand gate 6¹, has ascended to the top, discharged its contents, engaged the bar 30¹, pulling cables 32¹ or their equivalent and opening its coöperating filling gate 6¹ and 95 simultaneously closing the other filling gate 6¹ (shown on the left hand side). The cable 37¹ and 37² or its equivalent connects the filling gates in such manner that when one is closed the other is open.

If only one bucket or receptacle is used in combination with one loader, the cables 37 in Fig. 4 or cables 37² in Fig. 5 are connected to a bar similar to bar 30 arranged in the path of the bucket or receptacle counterweight (not shown).

The use and operation of my invention may be described as follows: When the skip or receptacle 5 in the right hand shaft referring to Fig. 3 has reached the top of the shaft and discharged its contents, the associate skip or receptacle 5 in the left hand shaft, has reached the position shown in Figs. 1 and 3. In descending to the foot of its shaft, the receptacle 5 has engaged the bar 30, or its equivalent, arranged within its path, drawing it between the guides 31 to its lowest position, as shown in Fig. 1, thereby exerting a pull on the cables 32 or their equivalent and revolving the loader filling gate 6 about its pivots 8 into closed position, shown in Figs. 1 and 3. Simultaneously the filling gate of the other loader is opened; the two gates being connected (by cables 37 passing over sheaves 39 and 40) in such manner that when one is closed the other is open, shown clearly in Figs. 3 and 4. When only one receptacle is used in combination with one loader the cables 37 are attached to a bar similar to 30, arranged either in the

path of the counterweight of the receptacle or extended to the top of the shaft so that the filling gate is opened when the skip or receptacle discharges, and closed, when it reaches the loader. However, before reaching the foot of the shaft and landing on the supports 29 the angle or projection 19, on the receptacle, engages the extending levers 18 operating the bars 13 upwardly, so that the latches 11 disengage the projections 9^b and the pressure of the material against the gate plate 9 causes the discharge gate to open. This extension 19 is located on the receptacle at such a point and operates the levers 18 only when the roller 20 (at the top part of the receptacle) is just under the discharge gate 9, so that as the bucket or receptacle descends, the gate opens gradually and forms an extending slope with the measuring chute bottom 4^a. When the receptacle reaches the landing points 29 as shown in Fig. 3, it has received a measured quantity of material and is ready to be hoisted or conveyed to its discharging point. In hoisting or rising, the receptacle 5 closes the discharge gate 9 which is counterweighted at 9^a on the sides 9^b so that the gate positively closes and is latched by the latches 11 pivoted on the sides of the measuring chute 4. When the receptacle rises, the projecting part 19 passes the extending levers 18 by swinging same about their pivot, as shown in dotted lines in Fig. 1. After the receptacle has passed by, the pivoted ends drop to normal or operative position by gravity. It may now be noted that the measuring chute 4 of the loader coöperating with the loaded receptacle (which is being hoisted) is empty, with both gates of the loader in closed position, and it remains empty until the loaded receptacle reaches the top of the shaft discharging its contents and the other empty bucket reaches the foot of the shaft operating the filling gates so that it closes its loader filling gate and opens the coöperating filling gate of the other loader. In this way no measuring chute is refilled until its coöperating receptacle reaches the top of the shaft and the other receptacle, (or counterweight when one receptacle is used) reaches the foot of its shaft, thus preventing a receptacle receiving a double load in case of being lowered into the foot of the shaft before discharging its contents.

Fig. 2 shows a sectional elevation of a loader with the discharge gate 9 closed, the measuring chute 4 filled and the filling gate 6 brought to an open position by the other receptacle (or counterweight), and thus the operation continues, each descending bucket or receptacle alternately operating the filling gates, discharging the measuring chute, receiving the measured quantity of material and then conveying the material to the storage bins. It may be noted that the re-

ceptacle could be arranged to travel either vertically (as shown in the drawings) on an incline or laterally without departing from my invention.

Having thus described my invention it is obvious that various immaterial modifications may be made in the same without departing from the spirit of my invention, hence I do not wish to be understood as limiting myself to the exact form or construction of parts herein shown and described or uses mentioned.

I claim as my invention:

1. In an apparatus of the kind described and in combination, a hoisting bucket, a material receiving bin, a stationary measuring hopper, an undercut gate arranged within said stationary measuring hopper to control the flow of material from said receiving bin into said measuring hopper, a discharge gate for said stationary measuring hopper, and independent means controlled by the hoisting bucket for independently operating said gates to fill and discharge said measuring hopper.

2. In a device of the kind described and in combination, a material receiving bin, a hoisting bucket, a measuring and loading device comprising a stationary measuring chute having an inclined bottom, side walls, an under-cut filling gate at one end, and a discharge gate at the other end, said filling gate being pivoted to said side walls and arranged to rotate within said measuring chute, means for operating said under-cut filling gate, and independent means for operating said discharge gate, both of said means controlled by the hoisting bucket.

3. In a device of the kind described and in combination, a material receiving hopper, a movable receptacle, a measuring and loading device comprising a single load stationary measuring bin with a bottom sloping down toward said receptacle, a curved, pivoted gate arranged within said measuring bin and operating to control the flow of material from said receiving hopper into said measuring bin, a discharge gate to control the flow of material from said stationary measuring bin into said receptacle, and independent means interposed in the path of said receptacle for independently operating said gates.

4. In a device of the kind described and in combination, a material receiving hopper, a hoisting receptacle, a measuring and loading device comprising, a stationary measuring chute, a pivoted, curved, gate plate mounted within said stationary measuring chute, a discharge gate for said measuring chute, means for rotating said curved, gate plate into open position to fill the measuring chute, and independent means for rotating said curved gate plate into closed position, and means for releasing said discharge

- gate when the hoisting receptacle reaches the loading point.
5. In a device of the kind described and in combination, a material receiving hopper, a bucket, a bucket shaft, a measuring and loading device comprising a stationary measuring chute, a curved, pivoted gate operative within said measuring chute, a discharge gate for said measuring chute, a means for rotating said curved, pivoted gate into open position to fill the measuring chute, and independent means for reversing the rotation of said curved, pivoted gate, said means for controlling said curved, pivoted gate arranged to open said curved, pivoted gate when said bucket has reached the top of said bucket shaft and close said curved, pivoted gate when said bucket reaches the foot of said shaft, and means arranged at the foot of said shaft for releasing said discharge gate to load the bucket.
6. In a device of the kind described and in combination, a material receiving hopper, a bucket, a shaft, a measuring and loading device comprising a stationary measuring chute, a curved, pivoted gate, operative within one end of said measuring chute to control the inflow of material, a discharge gate at the lower end of said chute to control the discharge of material, a plurality of means coöperating to alternately rotate said pivoted, curved gate whereby said pivoted, curved gate is opened when said bucket reaches the top of said shaft and closed when said bucket reaches the foot of the shaft, and independent means for releasing said discharge gate to load the bucket.
7. In a loading and unloading apparatus, the combination of a shaft and two hoisting buckets, a receiving hopper and two measuring and loading devices arranged between said receiving hopper and said shaft, each of said measuring and loading devices comprising a stationary measuring chute, a curved filling gate to control the flow of material from the receiving hopper into the measuring chute, and a discharge gate for the measuring chute, means controlled by the buckets for operating said discharge gates and independent means for operating said curved filling gates, means connecting the filling gates in such manner that when one is in open position the other is in closed position.
8. The combination in loading and unloading apparatus of a pair of shafts, a movable bucket in each shaft, a material receiving hopper, an automatic measuring and feeding device at the foot of each shaft, comprising a rotatable curved filling gate, a stationary measuring receptacle, and a discharge gate adapted to retain the measured quantity of material within said sta-
- tionary measuring receptacle, means controlled by the buckets for releasing said discharge gates to load said buckets, means for operating said rotatable curved filling gates so that they simultaneously operate in opposite senses, said means arranged so that each bucket alternately operates both filling gates.
9. In a device of the kind described and in combination, a material receiving hopper, a pair of conveying receptacles, a pair of measuring and loading devices arranged to control the flow of material from the receiving hopper to the conveying receptacles, each measuring and loading device comprising a stationary measuring chute, a curved pivotally mounted filling gate arranged between the receiving hopper and said measuring chute and operating with an undercut movement to cut off the flow of material from the receiving hopper to the measuring chute, a discharge gate for the measuring chute, and means interposed in the path of the conveying receptacle for releasing said discharge gate, means connecting the curved filling gates so that they simultaneously operate in opposite senses, and means arranged so that each conveying receptacle alternately operates both filling gates.
10. In a device of the kind described and in combination, a pair of shafts, a bucket movable in each of said shafts, means for alternately hoisting said buckets and returning same to the foot of their respective shafts, a material receiving hopper at the foot of each shaft and intermediate each receiving hopper and shaft, a measuring feeder comprising a stationary measuring chute, a filling gate arranged to control the flow of material from said receiving hopper to the measuring chute, a discharge gate to control the flow of material from the measuring chute to the bucket, means controlled by the buckets for alternately and independently operating said filling and discharge gates of each feeder, means connecting the filling gates of both feeders so that they simultaneously operate in opposite senses, one to close and the other to open.
11. In an apparatus of the character described, the combination of a hoisting bucket, a stationary material measuring chute, an inlet gate therefor disposed between the chute sides, an outlet gate for said chute adapted to retain the measured material, and independent means for controlling said gates, whereby the outlet gate is movable to closed position while said inlet gate remains stationary in closed position.
12. In an apparatus of the character described, the combination of a hoisting bucket, a stationary inclined material measuring chute, a pivotally mounted inlet gate therefor arranged between the chute

sides, an outlet gate for said chute adapted to retain the measured material, a plurality of means for controlling said gates, whereby the outlet gate movable to closed position while the inlet gate remains stationary in closed position.

13. In apparatus of the character described and in combination, a hoisting bucket, a stationary material measuring chute, a curved pivotally mounted inlet gate therefor, disposed between the chute sides, an outlet gate for the same adapted to retain the measured material, and independent means for controlling said gates whereby said outlet gate is moved to closed position while said inlet gate remains stationary in closed position.

14. In an apparatus of the character described, the combination of a material receiving bin, hoisting apparatus, and a single

charge stationary measuring chute or hopper, a filling gate for said chute, means controlled by said hoisting apparatus for operating said filling gate, a discharge gate at the lower end of said stationary measuring 25 chute, means arranged for retaining said discharge gate in closed position and adapted to be released by said hoisting apparatus, said discharge gate retaining means arranged to permit the movement of the discharge gate from open position to closed position while said filling gate remains stationary.

In witness whereof, I have hereunto subscribed my name in the presence of two witnesses this 29th day of May, 1912.

FRANK J. SCHRAEDER, JR.
